PROCESS FOR MAKING PERCHLORATES

Joseph C. Schumacher, Los Angeles, Calif., assignor to Western Electrochemical Company, Los Angeles, Calif., a corporation of Nevada

Application October 31, 1945, Serial No. 625,857

6 Claims. (Cl. 204—82)

1

This invention relates to a process for making perchlorates and particularly perchlorates of the alkali metals.

One object of the invention is to provide an improved process for making alkali metal perchlorates. Another object is to provide an economical method for making potassium perchlorate by the electrolysis of sodium chloride. A further object is to provide means for separating potassium perchlorate in a pure state from the electrolyte of a perchlorate electrochemical process. Still another object is to provide a two stage electrochemical process for substantially completely converting sodium chloride to sodium perchlorate.

In general my process consists in the electrolysis of a substantially saturated aqueous solution of sodium chloride in the presence of sodium chromate and magnesium chloride as catalysts, and with a controlled pH value in the electrolyte. From the electrolyte of an electrolytic cell, the perchlorate is separated as potassium perchlorate by the addition of potassium chloride, the potassium perchlorate being much less soluble in water than the sodium salt. I have found that by starting with a high concentration of sodium chloride in the electrolyte and recirculating the electrolyte through an electrolytic cell repeatedly, that the conversion of the chloride to the perchlorate may be effected to the extent of about 90%, thus yielding an effluent electrolyte of high concentration in sodium perchlorate. I have also found that much greater efficiency may be attained by again electrolyzing the effluent electrolyte from the above mentioned first electrolytic cell in an auxiliary electrolytic cell where the electrolyte is recirculated in and out of the cell until only about one or two percent of the sodium chloride content remains, the balance having been oxidized up to the sodium perchlorate compound. I have also found that the addition of magnesium chloride, along with the sodium chromate, as a catalyst, greatly assists in preventing undesirable side reactions. It is believed that this is brought about by the formation of a coating on the cathode surfaces which enables the hydrogen to be discharged as molecular hydrogen before effecting unwanted chemical reduction of the chloride and perchlorates. The amounts of the sodium chromate and magnesium chloride may be varied, but it is desirable to keep them to as low an effective content as possible because of the additional cost of completely removing them from the mother liquor in the steps subsequent to the electrolysis. A minimum of three grams per liter of

2

sodium chromate and one gram per liter of magnesium chloride has been found to be effective, while amounts of sodium chromate up to 15 grams and of magnesium chloride up to 10 grams per liter have been successfully used, so far as the catalysis of the electrochemical reactions is concerned.

The first mentioned electrolytic cell is operated with a continuous feed into the cell and the continuous withdrawal of a proportion of the electrolyte, which is then accumulated to be used in charging the auxiliary cell, which is operated as a batch process in which the electrolyte is recirculated in and out of the cell until the desired conversion of the chloride to perchlorate has been attained. The electrolyte of the auxiliary cell is then discharged completely, and the cell refilled with a new charge consisting of the effluent electrolyte withdrawn from the first mentioned continuous cell which has been accumulated in an intermediary storage tank.

I have further found that the electrochemical change from the chloride to the perchlorate is facilitated by maintenance in the electrolyte of a pH value of 6.0 to 6.8, a temperature of about 55° C., and the presence therein as catalyst of small amounts of sodium chromate and of magnesium chloride.

My process will be understood by reference to the drawing Figure 7 which shows diagrammatically the flow of materials. The dissolver A is used to form an influent electrolyte by dissolving the proper proportions of solid sodium chloride, sodium dichromate, magnesium chloride, and sodium hydroxide in water, steam being conveniently introduced to assist in the solution of the salts and to heat the solution to a temperature of about 55° C. The influent electrolyte from the dissolver in a typical example contains about 500 grams of sodium chloride together with about 5 grams sodium chromate and 2 grams magnesium chloride per liter, and with enough sodium hydroxide to give a pH of 6.0 to 6.8. It has been found that if the influent electrolyte has a pH value in the range of 6.0 to 6.8, that it remains at about this acidity throughout the cycle of electrolytic reactions, but if the influent electrolyte starts at a pH value above this, for example 6.9, the pH value tends to rise to 7 and above during the electrolysis, with lowered efficiency. This solution is passed in a continuous stream into the first electrolytic cell B which preferably consists of an elongated steel trough with arrangements for water cooling both on the outside and by pipe coils intermediate the anodes, the

pipe coils and the side walls of the cell serving as cathodes. Such an electrolytic cell is described in my co-pending patent application Serial No. 625,859 filed October 31, 1945, now Patent No. 2,475,147, issued July 5, 1949, and shown in Figures 1 to 6 inclusive.

Figure 1 is a top elevational view of a preferred form of my electrolytic cell;

Fig. 2 is a side elevational view of the same with parts broken away to show the interior arrangement;

Fig. 3 is an end elevational view of the same;

Fig. 4 is a cross-sectional view taken on the line 4—4 of Fig. 2;

Fig. 5 is a cross-sectional view taken on the line 5—5 of Fig. 2; and

Fig. 6 is a cross-sectional view taken on the line 6—6 of Fig. 2.

Fig. 7 shows diagrammatically the flow of materials.

In general my electrolytic cell consists of an elongated trough-like steel tank having an electrically insulating cover through which extend thin platinum sheet electrodes supported by suitable holding members, with cooling coils disposed between electrodes, and cooling jackets provided on the outer side walls of the tank, the steel tank and attached steel parts inside the cell constituting the cathode.

Referring to the drawings, my electrolytic cell consists of an elongated steel tank 11 with an open top and outwardly extending flanges 12 around the upper edge. Channels for cooling liquid are provided by longitudinally placed steel jackets 13 welded to the two side walls 11A of the tank 11, these being subdivided by horizontal partitions 14 to distribute the circulating cooling liquid. Further control of the temperature in the cell is attained by the use of a tier of steel tubes 15 extending centrally through the electrolyte compartment of the cell between the anodes 17, the ends of these tubes being connected to manifolds 16 on the two ends of the tank 11 so that the cooling liquid may be circulated not only through the side wall jackets 13 but also through these tubes disposed between the platinum anode 17 within the electrolyte compartment of the cell. The cell cover plates 18 consist of sheets of chemically resistant artificial stone material, for example, sheets made of compressed mixtures of Portland cement and asbestos, which sheets are attached by bolting to the flange 12 around the upper edge of the tank. Slit openings 19 fitting the platinum electrode sheets 20 are provided in this artificial stone cover 18 for the insertion of the anodes. The steel surfaces of the tank 11 and the water-cooling tubes 15 in contact with the electrolyte serve as the cathode for the cell.

The electrolyte is introduced through the influent pipe 21a and is withdrawn through the overflow or effluent pipe 22a tube. The cell is especially adapted for use in a process requiring the circulation or recirculation of the electrolyte in and out of the cell but it may also be used in a discontinuous process or in a batch or intermittent process in which the cell is filled with electrolyte which remains in it until the electrochemical reaction is completed to the desired stage.

In most electrochemical processes of the type to which this cell is adapted, there is evolved a mixture of gases often in explosive proportions. In the case of the electrochemical oxidation of sodium chlorate to sodium perchlorate for example, varying amounts and proportions of hy-

drogen, oxygen, and chlorine gases are evolved, and it is necessary, in order to avoid explosions, to remove this gas or dilute it with another gas to a mixture which is no longer explosive. Provision is made in my cell for the introduction of a sweeping out gas through the influent pipe 23 and the removal of the mixture of gases from the effluent pipe 24.

In electrochemical reactions requiring the use of platinum anodes, it is important, because of the high unit cost of platinum to use as small a quantity of the metal as possible. My platinum electrodes 17 consist of a thin sheet 20 of platinum, about .006 inch thick, which is punched with numerous holes in order to provide ready circulation of the electrolyte through and around all portions of the platinum surface. The thin sheet of platinum is inserted through the cover plate 18 through an opening 19 provided therein. Above the cover plate, the upper end of the thin platinum sheet is pressed between relatively heavy sheets of copper 25, and the sandwich thus formed is bolted together between the vertical portions of L-shaped bars 26 by bolts 29, which in turn are bolted along the horizontal sides to the cover plates 18 by means of threaded studs 27 of headed machine screws set in holes in the artificial stone cover plates 18. In order to prevent twisting and buckling of the extremely thin electrode sheet within the cell, it is held in substantially fixed position by means of depending glass bars 28 which are suspended from and rigidly held closely adjacent the platinum sheets 20 in countersunk holes 30 in the cover plates 18, the glass bars being provided with flanges 31 to fit in countersunk holes, being cemented in place by suitable chemically resistant material. The glass bars 28 are disposed at intervals along the length of the electrode and extend as far as the depth of the platinum sheet.

The cathode of the cell consists of the surfaces of the steel tank and the steel tubes used for water-cooling which are in contact with the electrolyte. An upright bar member welded to the flange on one side at the top edge of the tank provides a convenient electrical connection for the cathode to the bus bars of the electrical system.

The voltage is maintained at about 5½ to 6 volts; the anode current density is about 140 amperes per square foot and the cathode current density is about 250 amperes per square foot. The recirculation also has the important function of keeping the electrolyte at a uniform composition, and of uniform temperature of about 55° C., both conditions being important in maintaining the optimum conditions for efficient production of perchlorate. There is also constantly withdrawn from the cell a stream of effluent electrolyte corresponding to the rate of feed of newly dissolved salt solution into the electrolytic cell as influent electrolyte. The withdrawn electrolyte is accumulated in a storage tank C from which it is withdrawn intermittently to charge the auxiliary electrolytic cell D. This charging liquid to the auxiliary cell, in a typical case, contained about 600 grams per liter of sodium perchlorate and about 60 grams per liter of sodium chlorate together with the sodium chromate and magnesium chloride in the concentrations of the original liquid. The liquid is charged into the auxiliary electrolytic cell in sufficient amount to fill it, and it is then electrolyzed between platinum anodes and steel cathodes at a voltage of 5½ to 6 volts, the cathode current density being at the begin-

ning about 140 amperes per square foot and the anode current density being about 250 amperes per square foot, this decreasing as the conversion to perchlorate becomes completed. The electrolyte in the auxiliary cell D is recirculated to produce a moving electrolyte which assists in the completion of the conversion of the remaining sodium chlorate to sodium perchlorate. As before this recirculation of the electrolyte has the advantage of bringing fresh electrolyte into contact with the electrodes and in sweeping out the gases which tend to form in layers on the electrode surfaces. The constant recirculation also keeps the electrolyte at a uniform temperature of about 55° C., and the composition of the electrolyte is kept uniform throughout the cell. When the auxiliary electrolyte has been substantially completely converted to sodium perchlorate, it is withdrawn from the cell into a storage tank. In the typical case which is being described, this liquor contained about 680 grams per liter of sodium perchlorate with only about 10 grams per liter of sodium chlorate along with the sodium chromate and magnesium chloride of the original charge.

The collected effluent electrolyte from the auxiliary cell is then withdrawn in batches from the storage tank and delivered to a precipitator F where it is treated with sufficient barium chloride to remove the chromate as insoluble barium chromate and also with sufficient sodium carbonate to remove the magnesium as insoluble magnesium carbonate. The liquid containing the precipitated barium chromate and magnesium carbonate solid particles is then pumped into a thickener tank G in which the insoluble solids are settled out and withdrawn as a sludge from the bottom of the tank, to be discarded or further treated for recovery of the several ingredients. The clarified liquor from the thickener G is treated in batches in the crystallizer K with a saturated solution of potassium chloride which has previously been dissolved in water in the dissolver J somewhat in excess of the theoretical amount necessary to precipitate out the potassium perchlorate. The crystallizer is provided with means for chilling the liquid in order to precipitate the relatively insoluble potassium perchlorate and after the crystals have attained a sufficient size for good separation, the mixture of crystals and mother liquor is passed through a centrifuge to separate them, the crystals being subsequently dried as substantially pure potassium perchlorate. The mother liquor containing small amounts of sodium and potassium chloride, perchlorate, and chloride is sent to waste or it may be reclaimed in separate processes.

While I prefer to use the two stage electrolytic process, the effluent electrolyte from the main cell may be treated in the precipitator F (omitting the auxiliary electrolytic cell), but the purity of the perchlorate salt is not so high, and the efficiency of the whole process is not as satisfactory. One principal advantage of the two stage process is that it permits operation of the main electrolytic step under a good power load factor, while only the auxiliary cell, especially toward the end of the cycle, need be operated with a poor load factor.

By my process, I am able to produce sodium perchlorate of high purity and with a current efficiency above 90%. These results are attainable because of the maintenance of optimum uniform conditions on the electrolytic cells, i. e., the constant recirculation to give a uniform elec-

trolyte composition, temperature, and acidity, and the removal of gas films from the electrodes; and the use of the main and the auxiliary electrolytic cell, which permits operation of the main cell under continuous feed conditions designed to convert most of the chlorate to perchlorate and the completion of the change to perchlorate in batch cells.

I claim:

10. 1. In the electrochemical conversion of an aqueous sodium chlorate solution to sodium perchlorate solution, the steps comprising essentially making an aqueous electrolyte consisting essentially of from about 500 grams per liter to 15 grams of sodium chromate and 1 to 10 grams of magnesium chloride being present per liter of solution as catalysts; and electrolyzing said solution between steel and platinum electrodes under electrical conditions increasing the perchlorate content while rapidly circulating said electrolyte out and into the electrolytic cell, and while maintaining the electrolyte in the cell at a uniform pH value in the range of 6.0 to 25. 6.8, and a uniform temperature of about 55° centigrade throughout the body of said electrolyte.
2. In the electrochemical conversion of an aqueous sodium chlorate solution to sodium perchlorate solution the steps comprising essentially making an aqueous electrolyte consisting essentially of from about 500 grams per liter to 30. a saturated solution of sodium chlorate, from 3 to 15 grams of sodium chromate and from 1 to 10 grams of magnesium chloride being present per liter of solution as catalysts; maintaining the electrolyte at a uniform pH value in the range from 6.0 to 6.8 and at a uniform temperature of about 55° centigrade; continuously feeding in 35. a stream of said solution as influent electrolyte to an electrolytic cell; rapidly recirculating said electrolyte while electrolyzing the electrolyte between steel and platinum electrodes under electrical conditions increasing the perchlorate content; and continuously withdrawing a portion of 40. said electrolyzed electrolyte as effluent at a rate corresponding to the rate of feeding in said influent electrolyte.
3. A two-stage electrochemical process for conversion of sodium chlorate to sodium perchlorate, comprising essentially (1) the process of claim 50. 2, in which is produced an effluent electrolyte consisting essentially of not less than 500 grams of sodium perchlorate, not more than about 10 percent by weight of sodium chlorate, from 3 to 15 grams of sodium chromate, and from 1 to 10 grams of magnesium chloride per liter; and 55. (2) the step of electrolyzing as a batch a quantity of said effluent electrolyte while maintaining a pH in the range from 6.0 to 6.8 and a temperature of about 55° C., between steel and platinum electrodes at a voltage sufficient to convert chlorate to perchlorate until substantially all of said sodium chlorate is converted to sodium perchlorate.
60. 4. A two-stage electrochemical process for conversion of sodium chlorate to sodium perchlorate, comprising essentially (1) the process of claim 2, in which is produced an effluent electrolyte 65. consisting essentially of about 600 grams of sodium perchlorate, not more than about 60 grams of sodium chlorate, from 3 to 15 grams of sodium chromate, and from 1 to 10 grams of magnesium chloride per liter; and (2) the step of 70. electrolyzing as a batch a quantity of said eff-

fluent electrolyte while maintaining a pH in the range from 6.0 to 6.8, and a temperature of about 55° C., between steel and platinum electrodes at a voltage in the range from 5½ to 6 volts, until substantially all of said sodium chlorate is converted to sodium perchlorate.

5. In the electrochemical conversion of an aqueous sodium chlorate solution to sodium perchlorate solution the steps comprising essentially making an aqueous electrolyte consisting essentially of about 600 grams per liter of sodium chlorate, from 3 to 15 grams of sodium chromate and from 1 to 10 grams of magnesium chloride being present per liter of solution as catalysts; maintaining the said electrolyte at a pH value in the range from 6.0 to 6.8 and at a uniform temperature of about 55° centigrade; rapidly recirculating the electrolyte through the cell continuously feeding in a stream of said solution as influent electrolyte to an electrolytic cell; electrolyzing the electrolyte between steel and platinum electrodes under electrical conditions increasing the perchlorate content; and continuously withdrawing a portion of said electrolyte, as effluent at a rate corresponding to the feeding in of said influent electrolyte.

6. In the electrochemical conversion of an aqueous sodium chlorate solution to a sodium perchlorate solution, the steps comprising essentially making a nearly saturated aqueous electrolyte of sodium chlorate in which is dissolved from 3 to 15 grams per liter of sodium chromate and from 1 to 10 grams per liter of magnesium chloride as catalysts; maintaining said solution at a uniform pH value in the range from 6.0 to 6.8 and at a uniform temperature of about 55°

centigrade; and electrolyzing said electrolyte between steel and platinum electrodes under electrical conditions increasing the perchlorate content while rapidly recirculating the electrolyte through the cell.
